(57) **CLAIM**

The ornamental design for a support chair for poured concrete reinforcement members, as shown and described.

DESCRIPTION

FIG. 1 is a perspective view, taken from the top, front, and right side, of a support chair for poured concrete reinforcement members, in accordance with a first embodiment of our new design.

FIG. 2 is a perspective view, taken from the top, front, and left side, of the support chair for poured concrete reinforcement members shown in FIG. 1.

FIG. 3 is a front elevation view of the support chair for poured concrete reinforcement members shown in FIG. 1, the rear elevation view being identical.

FIG. 4 is a right side elevation view of the support chair for poured concrete reinforcement members shown in FIG. 1, the left side elevation view being identical.

FIG. 5 is top plan view of the support chair for poured concrete reinforcement members shown in FIG. 1.

FIG. 6 is a bottom plan view of the support chair for poured concrete reinforcement members shown in FIG. 1.

FIG. 7 is a perspective view, taken from the top, front, and right side, of a support chair for poured concrete reinforcement members, in accordance with a second embodiment of our new design.

FIG. 8 is a perspective view, taken from the top, front, and left side, of the support chair for poured concrete reinforcement members shown in FIG. 7.

FIG. 9 is a front elevation view of the support chair for poured concrete reinforcement members shown in FIG. 7, the rear elevation view being identical.

FIG. 10 is a right side elevation view of the support chair for poured concrete reinforcement members shown in FIG. 7, the left side elevation view being identical.

FIG. 11 is top plan view of the support chair for poured concrete reinforcement members shown in FIG. 7; and,

(Continued)

FIG. 12 is a bottom plan view of the support chair for poured concrete reinforcement members shown in FIG. 7.
